(57) **CLAIM**

The ornamental design for a remote control for heating pad as shown and described.

DESCRIPTION

FIG. 1 is a front, left, and top perspective view of the first piece of a remote control for heating pad, showing my new design;

FIG. 2 is a rear, right, and bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a front, left, and top perspective view of the second piece of the remote control for heating pad;

FIG. 10 is a rear, right, and bottom perspective view thereof;

FIG. 11 is a front elevational view thereof;

FIG. 12 is a rear elevational view thereof;

FIG. 13 is a left side elevational view thereof;

FIG. 14 is a right side elevational view thereof;

FIG. 15 is a top plan view thereof;

FIG. 16 is a bottom plan view thereof; and,

FIG. 17 is a perspective view of the remote control for heating pad when the second piece is attached to the first piece.

The broken lines in the drawings depict portions of the remote control for heating pad that form no part of the claimed design.

1 Claim, 17 Drawing Sheets
